COAT AND HAT HOOK

Herbert E. Binder, Milwaukee, Wis.

Application December 28, 1936, Serial No. 117,941

2 Claims. (Cl. 248—217)

This invention relates to garment hangers and more particularly to a combination coat and hat hook.

An object of the present invention is to provide a hanger of the character mentioned which can be cheaply and economically constructed, readily and easily applied to a wall or other suitable support, and which is of such a construction and arrangement of parts as to insure the retention thereon of hats, coats or the like in a positive and efficient manner.

The invention together with its objects and advantages will be best understood from a study of the following description taken in connection with the accompanying drawing wherein:

Figure 1 is a side elevational view of the coat and hat hook and

Figure 2 is a front end elevational view thereof.

Referring to the drawing by reference numerals it will be seen that in the preferred embodiment of the invention the combination coat and hat hook is formed from a single length of wire rod or the like bent, shaped and dimensioned to provide an inclined arm 5 which at one end is provided with a reverse bend 6 that in turn merges into a U-bend or brace element 7 which latter at the closed end of the U is welded to the arm 5 as at 8. At the open end of the U the free side of the member 7 merges into a forwardly extending longitudinally curved hook 9 that in turn is provided with a reverse bend 10 that connects the hook 9 with a shank 11 the free end of which extends beyond the return bend 6 and is pointed and threaded to provide a screw 12.

Preferably there is welded or otherwise secured as at 13 to the combination coat and hat hook at the bend 6 a disc 14 which latter is suitably apertured to accommodate the shank of the securing hook 12.

On its outer or free end there is secured to the arm 5 a knob or head 15 which may be of wood covered with fabric, or enameled, and screwed or otherwise secured on to the free end of the arm 5.

In using the hanger the screw 12 is screwed into a wall or other suitable support until the disc 14 is brought into flat bearing engagement against the support with the arm 5 extending outwardly and upwardly from the support.

With the hanger thus secured to the support it will be seen that the arm 5 together with the knob 15 on the free end thereof will serve ad-

mirably as a hanger arm for a hat while the hook 9 may have the collar or other portion of a garment disposed thereover and will serve admirably for suspending the garment from the hanger.

It will be further found, in actual practice, that a garment hanger having the features of the present invention will be such as to retain garments, especially hats thereon in a manner as will not permit the hats to be readily knocked off of the arm 5 or otherwise displaced.

It is thought that a clear understanding and appreciation of an invention of this character will be had without a more detailed description.

Having thus described the invention, what is claimed as new is:

1. A garment hanger comprising a length of wire rod bent, shaped and dimensioned to provide a hat suspension arm provided at one end with a return bend merging into a U-shaped brace member secured at its closed end to said arm, and having one side at the open end of the U extended forwardly and longitudinally bowed to present a garment suspension hook, said garment suspension hook at its free end merging into a return bend, with the free end of the wire extending rearwardly from said return bend and extending beyond the first mentioned return bend with its terminal being tapered and threaded to provide an attaching screw whereby the hanger may be secured to a wall or analogous support.

2. A garment hanger comprising a length of wire rod bent, shaped and dimensioned to provide a hat suspension arm provided at one end with a return bend merging into a U-shaped brace member secured at its closed end to said arm, and having one side at the open end of the U extended forwardly and longitudinally bowed to present a garment suspension hook, said garment suspension hook at its free end merging into a return bend, with the free end of the wire extending rearwardly from said return bend and extending beyond the first mentioned return bend and its terminal being tapered and threaded to provide an attaching means whereby the hanger may be secured to a wall or analogous support, a knob on the free end of said hat supporting arm, and a disc member secured to the first mentioned return bend and apertured to accommodate the threaded screw forming terminal of the wire.

HERBERT E. BINDER.
